COOKSTOVE HOUSING

Milton A. Tuttle, Los Angeles, Calif., assignor to Lear Siegler, Inc., Santa Monica, Calif., a corporation of Delaware

Filed June 20, 1966, Ser. No. 2,750

Term of patent 14 years

(Cl. D81—4)

The drawing is a front perspective view of the cookstove housing. The rear is the same as the front with the exception of the control knob shown at the upper portion of the pedestal.

I claim:

The ornamental design for a cookstove housing, substantially as shown and described.
